(57) **CLAIM**

The ornamental design for a steering wheel as shown and described.

DESCRIPTION

FIG. 1 is a perspective view of a steering wheel showing my new design;

FIG. 2 is a front elevation view thereof;

FIG. 3 is a back elevation view thereof;

FIG. 4 is a side elevation view thereof; and,

FIG. 5 is an opposite side elevation view thereof.

The broken lines shown in all drawing views are for illustrative purposes only and form no part of the claimed design.
